UNITED STATES PATENT OFFICE.

HAROLD T. BLUM, OF GLENMONT, OHIO.

SWEATBAND FOR HEAD COVERINGS.

Original application filed June 23, 1927, Serial No. 201,002. Divided and this application filed September 19, 1927. Serial No. 220,547.

This invention relates to sweat bands for head coverings such as caps and similar devices, the invention herein disclosed being a division of the parent application for United States Letters Patent filed by me June 23, 1927, bearing Serial Number 201,002, and having for an object to provide a head covering sweat band wherein the band is so shaped and constructed that it may be effectually adjusted and will, with wearing of an equipped head covering, snugly engage over a portion of the wearer's head in a manner to retain the hair in a neatly or properly combed and groomed condition, thereby avoiding disarrangement or mussing of the hair as is commonly experienced with the wearing of caps having the conventional design of sweat bands therein.

Other objects of the invention will be in part obvious and in part pointed out herein-after.

In order that the invention and its mode of operation may be readily understood by those skilled in the art to which it appertains, I have in the accompanying illustrative drawings and in the detailed following description based thereupon, set out one possible embodiment of my invention.

In these drawings:

Figure 1 is a bottom plan view of the improved sweat band showing the same applied to a cap type of head covering and

Figure 2 is a transverse section through the same.

Having more particular reference to the drawings in connection with which like characters of reference will designate corresponding parts, I have, as hereinbefore indicated illustrated in this particular application, the improved sweat band as being arranged in a cap type of head covering indicated in its entirety by the numeral 1, the sweat band being of generally circular formation when arranged in the cap and composed of leather, imitation leather or of other suitable material, one marginal portion of which is stitched or otherwise suitably joined to the circular head receiving opening or border of the cap as is indicated by the numeral 2. The forward and rearward head engaging portions of the band 2 are formed comparatively narrow as is indicated by the numerals 3 and 4 whereas the opposite side head engaging portions of said band are materially widened as is indicated by the numerals 5 and 6, these

widened opposite side portions being sized according to the particular size or dimension of an equipped cap, as for example, they are approximately five inches wide in a cap of the conventional head size numbered seven, 60 whereas an equipped cap of a greater or lesser size would require a variance of dimensions accordingly.

With arrangement of the sweat band 2 in the cap as is shown in the accompanying drawing, the widened opposite side portions 5 and 6 are curved upon themselves as is indicated by the numeral 7 and these curved portions are adapted to follow and conform to the curvature of the head of a wearer of a cap equipped with the device. Consequently upon this, it will be understood that with arrangement of the cap upon the head of a wearer, the widened portions 5 and 6 of the band 2 will have snug engagement or disposition over the wearer's hair and because of this, the hair so engaged which will constitute the major portion of the suit, will be positively retained in neatly and properly combed or groomed condition against disarrangement or mussing during the period for which the cap is worn or possibly shifted during such wearing upon the wearer's head.

Furthermore, it will be understood that because of the engagement of the widened opposite sides 5 and 6 of the band 2 over the major portion of the hair of a wearer's head, the equipped cap may be readily removed from the head without liability of disarranging the grooming of the same, especially because of the fact that the body portion of the cap proper will be prevented from coming into striking or rubbing engagement with the hair during removal of the cap or for that matter, during engagement or placing of the same upon the wearer's head or adjustment thereof subsequently to such placement.

With a view toward providing the improved form of sweat band with means whereby the same may be minutely adjusted to the head of a wearer to the desired nicety in order that an effectual retention of the hair in properly combed or groomed arrangement will be insured, I secure to the inner marginal portion of one of the widened parts of such band (the widened part 5 herein) one end of a transversely disposed strap or flexible piece 8, as is indicated at 9, the opposite or free end of said strap carrying the socket element of a separable fastener or so-called

"snap" 10, which, as is shown in the Figure 2, is adapted to be selectively engaged with any one of the transversely disposed series of studs or tongue devices 11 arranged upon and suitably secured to the intermediate and inwardly disposed or free portion of the widened part 6 of the band 2. Because of this provision of the strap 8 and the separable fasteners constituted by the elements 10 and 11, it will be seen that the wearer of a cap equipped with the improved band may effectually adjust the sweat band to a position whereat it will comfortably and efficiently engage over his head, subsequently to which the cap may be quickly and conveniently engaged with the head and comfortably worn with the assurance of retention of the wearer's hair in position and against undesirable disarrangement.

20 I claim:

1. A hair retainer for caps comprising a dome shaped body portion, means for attaching the lower edges of said body portion to the cap whereby it will extend within the head receiving opening thereof, the medial part of said body portion being cut away to form a pair of oppositely disposed flanges

and an adjustable strap extending across the cut away portion of said body and connecting said flanges.

30

2. A combined sweat band and hair retainer for caps comprising a body portion, flanges formed with the opposite sides of said body portion, a strap having one end secured to one of said flanges and an adjustable connection between the opposite end of said strap and the other of said flanges.

35

3. A combined sweat band and hair retainer for caps comprising a dome shaped body portion adapted to be received within the head receiving opening of the cap and snugly fit throughout its area with the head of the wearer, said body portion being cut away to form oppositely disposed flanges, a transversely disposed strap secured at one end to one of said flanges and separable fastening devices carried upon the remaining end of said strap and upon a portion of the other of said flanges whereby to permit of adjustable interconnection between said flanges of the body.

40

In witness whereof I have hereunto set my hand.

HAROLD T. BLUM.
